UNITED STATES PATENT OFFICE.

CLAUS ERICKSON, OF IRONWOOD, MICHIGAN, ASSIGNOR OF ONE-FOURTH TO JOSEPH SMITH, OF IRONWOOD, MICHIGAN.

METALLIC RAILWAY-TIE.

1,094,847.

Specification of Letters Patent. Patented Apr. 28, 1914.

Application filed January 24, 1914. Serial No. 814,221.

To all whom it may concern:

Be it known that I, CLAUS ERICKSON, citizen of the United States, residing at Ironwood, in the county of Gogebic and State of Michigan, have invented certain new and useful Improvements in Metallic Railway-Ties, of which the following is a specification.

The present invention relates to a combined metallic railway tie and means for fastening the rails thereto, the object of the invention being to provide a simple and inexpensive device of this character which is composed almost entirely of metal and embodies novel features of construction whereby the rails are held securely in position, although cushioning means is provided to prevent the objectionable hammering and noises which are always incident to the use of an all metal tie.

A further object of the invention is to provide a device of this character which admits of the rails being easily and quickly placed in position or removed therefrom, which provides a firm support for the rails, and which can be used as a satisfactory and inexpensive substitute for wooden ties.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a plan view of a railway tie provided with rail fastening means constructed in accordance with the invention. Fig. 2 is a longitudinal sectional view through the same. Fig. 3 is a detail perspective view of one of the rail clamping members. Fig. 4 is a similar view of one of the rail supporting plates. Fig. 5 is a similar view of one of the rail supporting and cushioning blocks. Fig. 6 is a longitudinal sectional view through a railway tie provided with a modified form of rail fastening means, and Fig. 7 is a detail perspective view of one of the rail supporting plates employed in connection with the modified construction of the invention.

Corresponding and like parts are referred

to in the following description and indicated in all the views of the drawings by the same reference characters.

Specifically describing the embodiment of the invention illustrated by Figs. 1 to 5 of the drawings, the numeral 1 designates a metallic railway tie which has a substantially U shaped cross section and may be conveniently formed from the ordinary commercial sections of channel iron. The base of the tie may rest directly upon the road bed with the flanges projecting upwardly from opposite sides thereof. The rails 2 cross opposite ends of the tie in the usual manner and rest upon cushioning and supporting blocks 3 positioned between the side flanges of the tie. These cushioning and supporting blocks 3 may be formed of wood so as to eliminate unnecessary and objectionable noise incident to the passage of rolling stock over the track, as well as to prevent destructive hammering action which is usually present where an all metal construction is employed. The base of the tie 1 is provided upon opposite sides of the supporting blocks 3 with openings 4 designed to receive downwardly projecting hooked lugs 5 at the outer ends of rail clamping members 6. These rail clamping members 6 preferably have a wedge shaped formation, the tapered outer ends thereof terminating in the downwardly projecting hooked lugs 5 adapted to pass through the openings 4 in the base of the tie 1, while the inner ends thereof are adapted to abut against the supporting blocks 3 and are provided at the upper portions thereof with rail engaging wings 7 adapted to project over and engage the basal flanges of the rails 2. The inner faces of the rail clamping members 6 are formed with bolt receiving openings 8 which register with a bolt receiving notch 9 in the top of the rail supporting block 3, the outer ends of the clamping members 6 being recessed from the top thereof as indicated at 6a to provide a clearance space for the bolt heads and nuts, as well as to eliminate unnecessary metal and reduce the weight and cost of manufacture. Suitable fastening members such as the bolts 10 are received within the notches 9 of the rail supporting blocks 3 and pass through the openings 8 of the rail clamping members 6. When these bolts 10 are removed,

the rail clamping members 6 can be swung upwardly about the hooked lugs 5 as a pivot center so as to admit of the rails 2 being readily placed in position upon the blocks 3 or removed therefrom. After the rails have been properly positioned, the rail clamping members 6 are swung downwardly into the position indicated by Fig. 2 and the bolts 10 inserted in position. As these bolts 10 are tightened, the rail clamping members are drawn together, and since the bolt acts horizontally in a plane above the hooked lugs 5, this tends to draw the rail clamping members both downwardly against the base 15 of the tie 1 as well as inwardly toward the rail supporting block 3. The wings 7 of the rail clamping members 6 are thus brought into a firm engagement with the basal flanges of the rails 2 so as to hold the 20 rails securely in position. The tapered outer ends of the two rail clamping members 6 at opposite ends of the tie 1 are provided with the spaced upstanding lugs 12 adapted to engage corresponding notches 13 in the 25 outer end of an inclined rail supporting and brace plate 14. This brace plate 14 rests squarely upon the inclined upper face of the rail clamping member and is provided at its upper end with a rail supporting surface 14^a 30 adapted to engage the lower surface of the head of the rail at the outer side thereof. The rails are thus supported both at the bases and heads thereof and are securely held against vertical displacement or spreading. 35

A slight modification of the invention is illustrated by Figs. 6 and 7. The character 1^a designates the tie which has a channel formation as in the previous instance. 40 Openings 4^a are also provided as in the previous instance, although in forming these openings 4^a the metal of the base of the tie is pressed upwardly to provide suitable keepers 16. The rail clamping members 6^b have 45 a wedge shaped or tapered formation and are similar in construction to the rail clamping members 6, rail engaging wings 7^a being provided at the top of the inner ends thereof, while they are recessed in a similar manner to receive the fastening members or bolts 10^a. The tapered outer ends of the rail clamping members 6^b are provided with the lugs 5^a which are straight and project longitudinally therefrom, instead of having a 55 hooked formation and projecting downwardly as in the former instance. These lugs 5^a are inserted within the openings provided by the keepers 16 and provide a pivot center about which the rail clamping members 6^b can be swung upwardly. After the rails have been positioned and the rail clamping members 6^b swung downwardly, the bolts 10^a are inserted and tightened, acting as previously described to draw the 60 wings 7^a into a close engagement with the

basal flanges of the rails. In connection with the modification, a brace plate 14^b may also be employed, the said brace plate resting upon the inclined upper surface of the rail clamping member 6^b and being provided at its lower end with a notch 18 adapted to engage the keeper 16 and at its upper end with a rail supporting surface 19 adapted to bear against and engage the lower surface of the rail head. The rails are thus securely held in position, although they can be readily removed at any time. In this modified form of the invention the lower surface or bottom of the tie is absolutely flat with no projections, and this may be found preferable for certain uses. 70 75 80

In carrying out the invention the two rail clamping members 6 preferably differ slightly in length, one of the said members being about one-quarter inch longer than the other member. With this construction the gage of the track can be made a trifle wider or trifle narrower by reversing the position of the two clamping members 6. By reversing the position of the two clamping members on both sides of the track, a difference of one-half inch could be made in the gage of the track, and this might be required on some curves. 85 90 95

Having thus described the invention, what I claim as new and desire to secure by Letters Patent, is:—

1. In a device of the character described, the combination of a tie, a rail supporting block resting upon the tie, a rail upon the rail supporting block, a pair of substantially wedge shaped rail clamping members mounted upon the tie on opposite sides of the block, the tapered outer ends of the rail clamping members being formed with lugs which each have a loose pivotal connection with the tie, while the inner ends of the rail clamping members are formed with rail engaging wings, and a fastening member extending under the rail and connecting the rail clamping members. 100 105 110

2. In a device of the character described, the combination of a tie member having spaced openings therein, a rail supporting block resting upon the tie at a point between the openings, a rail upon the rail supporting block, a pair of rail clamping members mounted upon the tie member on opposite sides of the block, the outer ends of the rail clamping members being formed with lugs loosely engaging the openings of the tie member while the inner ends thereof are formed with rail engaging wings, and a bolt passing under the rail and connecting the rail clamping members. 115 120 125

3. In a device of the character described, the combination of a tie member having spaced openings therein, a rail supporting block resting upon the tie at an intermediate point between the openings, a rail upon the 130

- 5 rail supporting block, a pair of wedge shaped clamping members mounted upon the tie member on opposite sides of the block, the tapered outer ends of the rail clamping members being provided with downwardly extending hooked lugs passing through the openings of the tie member and engaging the bottom thereof, while the thick inner ends of the said members are provided 10 at the top thereof with wings adapted to engage the basal flanges of the rail, and a bolt member extending under the rail and connecting the wedge shaped clamping members.
- 15 4. In a device of the character described, the combination of a channel tie member, a rail supporting block resting upon the tie member and positioned between the flanges thereof, a rail upon the rail supporting 20 block, a pair of wedge shaped rail clamping members applied to the tie on opposite sides of the rail supporting block, the tapered outer ends of the rail clamping members each having a loose pivotal connection with 25 the tie member, while the inner ends thereof are provided with wings adapted to fit over and engage the basal flanges of the rail, and a bolt passing through the rail supporting block and connecting the rail clamping 30 members.
- 35 5. In a device of the character described, the combination of a channel tie member having spaced openings in the base thereof, a rail supporting block resting upon the tie member and positioned between the flanges thereof, said block having a bolt receiving notch in the top thereof, a rail resting upon the said block, a pair of rail clamping members mounted upon the tie on opposite sides of the block, the outer ends of the rail clamping members being formed with lugs loosely engaging the openings of the tie member while the inner ends thereof are formed with wings adapted to extend over 40
- 45 and engage the basal flanges of the rail, said rail clamping members having bolt receiving openings registering with the bolt receiving notch of the block, and a clamping bolt connecting the rail clamping members and positioned within the bolt receiving notch of the 50 block.
- 55 6. In a device of the character described, the combination of a tie member, a rail supporting block resting upon the tie member, substantially wedge shaped rail clamping members mounted upon the tie member on opposite sides of the rail supporting block, the tapered outer ends thereof each having a loose connection with the tie member, while the inner ends thereof are formed 60 with wings adapted to project over and engage the basal flanges of the rail, a clamping bolt connecting the rail clamping members, and a brace plate resting upon the inclined top of one of the wedge shaped rail clamping members and provided with a rail supporting surface engaging the head of the rail.
- 65 7. In a device of the character described, the combination of a tie member, a rail supporting block resting upon the tie member, a rail upon the rail supporting block, wedge shaped rail clamping members applied to the tie member upon opposite sides of the block and provided at their inner ends 70 with wings adapted to extend over and engage the basal flanges of the rail, and a brace plate resting upon the inclined upper surface of one of the rail clamping members and provided with a rail supporting surface 75 engaging the head of the rail.

In testimony whereof I affix my signature in presence of two witnesses.
